CLAIM

The ornamental design for an electronic lid device for a beverage, as shown and described.

DESCRIPTION

FIG. 1 is a perspective view of an electronic lid device for a beverage showing our new design;

FIG. 2 is a top plan view thereof;

FIG. 3 is a bottom plan view thereof;

FIG. 4 is a front elevational view thereof, the rear elevational view being a mirror image of the front elevational view;

FIG. 5 is a right side elevational view thereof;

FIG. 6 is a left side elevational view thereof; and,

FIG. 7 is a perspective view thereof, shown in an exemplary condition of use.

The evenly broken lines are shown for the purpose of illustrating environmental subject matter and parts of the article that form no part of the claim. The dot-dash broken lines define the boundaries of the claim and form no part thereof.
